UNITED STATES PATENT OFFICE.

SAMUEL REICH, OF NEW YORK, N. Y.

DESIGN FOR A DOLL.

Application filed May 10, 1922. Serial No. 2,174. Term of patent 8½ years.

To all whom it may concern:

Be it known that I, SAMUEL REICH, a citizen of the United States, residing in the city of New York, borough of Manhattan, in the county and State of New York, have invented a new, original, and ornamental Design for Dolls, of which the following is a specification, reference being had to the accompanying drawings, forming a part thereof, and of which—

Figure 1 is a front elevation and Fig. 2 is a side elevation of a doll showing my new design, the leading feature of novelty of which is in the manner in which the skirt is parted so as to receive and extend over the top of the head of the doll.

I claim:

The ornamental design for a doll as shown and described.

SAMUEL REICH.
